(57) **CLAIM**

The ornamental design for gazebo, as shown and described.

DESCRIPTION

FIG. 1 is a front perspective view of a gazebo showing my new and original design;

FIG. 2 is a front side elevation view thereof;

FIG. 3 is a back side elevation view thereof;

FIG. 4 is a left side elevation view thereof;

FIG. 5 is a right side elevation view thereof; and,

FIG. 6 is a top plan view thereof.

Views of the bottom side of the gazebo have been omitted because such side is flat and devoid of surface ornamentation.
